UNITED STATES PATENT OFFICE.

HARRY A. ADAMS, OF BOSTON, MASSACHUSETTS, ASSIGNOR TO JOHN F. RYAN, OF BELLows FALLS, VERMONT.

STRIP-SERVING DEVICE.

1,212,873.

Specification of Letters Patent. Patented Jan. 16, 1917.

Application filed June 22, 1914. Serial No. 846,511.

To all whom it may concern:

Be it known that I, HARRY A. ADAMS, a citizen of the United States, residing at Boston, in the county of Suffolk and State of Massachusetts, have invented new and useful Improvements in Strip-Serving Devices, of which the following is a specification.

This invention relates to improvements in strip serving devices.

10 More particularly it relates to apparatus for holding a supply of dry tape and delivering it in adhesive condition as it is drawn forth, in sections of any desired length.

15 Among the particular objects of the invention are the provision of means by which the leading end of the supply of tape, being the end remaining after a moistened section has been severed, is kept dry, and yet is so held that it can conveniently and quickly be moistened, beginning with its very tip end; and can be moistened thoroughly even though it be thick and stiff, by being pressed against the moistener with a high degree of 25 tension after being started with a minimum of tension.

Other objects are to provide means by which the tape may be preliminarily prepared for use as a label, by writing an address or other matter upon it; apparatus which is capable of holding with equal facility tape of many different widths; of holding this without the application of any friction to the supply roll, while meeting at 35 the same time the above defined requirements as to draft tension, and of doing this with a roll of any diameter, or of large variation of diameter within commercial limits. Also to provide apparatus suitable for use with 40 gummed tape wound with the gum side in or out, and in the former case, providing for the very complete exposure of that portion of the strip which is being drawn forth so that it can be severed with precision at any 45 predetermined line, a feature which is useful in case the tape consists of a succession of printed labels.

It is also an object of the invention to provide apparatus having the very large 50 storage capacity for moistening water which is characteristic of the structure illustrated, and in general to provide apparatus having the other advantages that are characteristic of the invention herein disclosed.

55 These objects are accomplished by the sim-

ple, effective and quickly adjustable construction set forth herein, reference being had to the accompanying drawings, but it is to be understood that the patent is not limited to the particular embodiment of the invention here chosen for illustration; and that it is the purpose of the patent to cover in the appended claims whatever features of patentable novelty exist in the invention disclosed.

In the accompanying drawings: Figure 1 is a side elevation, in central section, through apparatus embodying the invention; Fig. 2 is a plan of the same, in section on the line 2—2 of Fig. 1; Fig. 3 is an end elevation of 70 a fragment, in section on the medial vertical plane through the roll and standard in the top part of Fig. 1 beside it; Fig. 4 is a section of a guide, being a detail, seen in end elevation, on the line 4—4 of Fig. 2; Fig. 5 is an end elevation, viewed from the rear; Fig. 6 is a view of a modification of a detail; and Fig. 7 is a view of a modification of another detail.

Referring to the accompanying drawings, 80 10 represents a base having suitable feet 11, which may be rubber pads. The base carries at one end a pair of uprights 12 for holding a supply roll of tape; in its middle a box or reservoir 13 for containing water, 85 in which at the front end a moistening roll 14 is immersed; and, between the roll and the uprights, and over the main portion of the reservoir, a platen 15 which may serve several purposes more fully defined hereinafter. The reservoir 13 consists of a simple box, preferably of metal, water tight at its sides. This may preferably have a removable cover 16 covering the greater part of its surface, but it is open at its forward end 90 in order to expose the roll 14 which is journaled in blocks 17 carried on the inside of the reservoir, which roll projects up above the level of the platen 15, as illustrated in Fig. 1. Under the bottom of the base is a spring latch 18, projecting forward and there reaching up and adapted to engage the front end of the reservoir and hold it in place. The platen 15 comprises a suitable flat plate lying on the top of the base and 95 and wide enough to receive the maximum width of tape for which the apparatus is adapted. This may be held rigidly in place by screws 19. Upon it tape guides 20 are mounted movably, with clamping screws 21 100

2 UNITED STATES PATENT OFFICE

This being so, it is only necessary, in order to get hold of the tape, for the user to press his finger lightly upon the top of the tape on the platen near the blade and then to draw it toward the moistening roll. The tape moves easily and is thus projected forward in a plane parallel to and just above the plane on the platen 15, so that the leading edge of the tape strikes the roll 14 and is deflected upward thereby to a position over the roll where the user can seize it with his fingers, and so can draw forth as much more of the tape as he wishes. As the tape issues at a level below the level of the top of the roll, it can be in contact with a considerable arc of the roll while being drawn, and can be pressed down hard upon it while so being drawn, on account of the efficiency of the tension, and so be thoroughly moistened. If the flat style of blade 24" be used, the tension will be provided in any other suitable means, as by providing axial compression of the supply roll 26, according to methods that are already well known and in extensive use and therefore do not need to be described here, or according to any other suitable method.

The guide roll 27 may be held by ears 28 projecting from the base and may conveniently be formed by journaling one end of this roll, as at 29, (Fig. 2) in a simple hole through the ear, and by journaling the other end, 30, in a slot 31, seen in Fig. 1 extending upward and backward through the other ear. Furthermore said slot may be cut with a slightly convex upper side, having a minimum width a trifle less than the diameter of the pin 30, which is to enter it, so that in order to get the pin 30 in, the slot has to be sprung open slightly, the pin then snapping down into its seat at the inner end of the slot. A roll so held is easily removable with a little pressure in the upward and backward direction in which the slot extends, but is never removable by draft of the tape, because that draft is in a direction which draws the roll farther into the slot.

The means provided for holding the supply roll of tape consists of the upright standards 12 which, with their attached parts, are of peculiar construction. Each piece has near its top a series of slots 32 extending into it in an oblique downward and forward direction and having a circular enlargement 33 at the inner end, constituting a seat for the axial pins 34, one of which projects from a disk 35 at each side of the supply roll of tape. These axial pins may carry clamping screws and nuts which are useful for holding the disk in place on the uprights when there is no roll of tape present, as seen in Fig. 5. If the nuts are used it would ordinarily be necessary to make them respectively with right handed and

left handed threads to prevent their being unscrewed when the tape roll turns, and even then the holder would be available for use for tape wound in one way only, either with the gum side in or with the gum side out.

Another feature of the invention is the provision of short pins 37 (Fig. 1) set on the outer side of the disks 35 at a little radial distance from the axial pins, which pins 37 follow the axial pins 34 into the slots 32, and when therein prevent the disks from rotating. The connection of the disks to the supply roll of tape is by short studs 38, preferably not exceeding a quarter of an inch in length, adapted to enter loosely the axial hole in the wooden spool on which the supply roll of tape is customarily wound. When the apparatus is in use there is no direct connection between the pair of disks 35 between which the roll 26 is positioned, and the roll is therefore instantly removable by lifting it and the two disks diagonally upward and backward out of the slots 32, after loosening the two nuts 36 a fraction of a turn. A fresh roller can be inserted with equal facility. If the clamping nuts 36 be omitted, the pins 37 may be omitted, and the disk 35 will then have the very simple aspect seen in Fig. 6, with only a short smooth stud 34' on one side which projects axially into a seat 33, and a short smooth stud 38 on the other side which projects into the roll of tape. The disks are then held in place on the uprights 12 by the fact that they are on the inner side of these uprights, and that the space between them is filled by the roll of tape. Under these circumstances the rotation of the disks 35 will do no harm if it occurs.

In the preferred form of the invention, in which the tilting blade 24 is used for obtaining tension, the uprights 12 are set at distances apart from each other such that they exert no appreciable pressure upon the supply roll. Each disk is merely held stationary on its standard 12 and the supply roll of paper turns loosely upon the studs 38. The described tape support is, however, well adapted to impose tension upon the tape if that be desired, and to do so under conditions conducive to uniformity of action of the apparatus as a whole at all times and with all widths of tape; without need of adjustment for changes in diameter of the supply roll.

As illustrated, (Fig. 5) the standards themselves consist of L-shaped pieces of flat metal, the base 12' of each being the horizontal part of the L, and the upright parts of both having their cooperating axle pin seats 33 (Fig. 1) at identical elevations. To support them, the main base of the apparatus has a suitable sill 10', at the rear and extending transversely of the apparatus, pro-

4

1,212,873

vided on its upper surface with a number of corrugations 39 extending in the longitudinal direction of the apparatus. The tip end of the base of each L has a little tooth-like turned-down edge 40 which is adapted to engage in any one of the corrugations 39, and this sill is pierced by slots 41, running transversely of the apparatus, through which slot goes a bolt 42 with a clamping nut 43 on top, so that the base 12' may be clamped fast to the sill. This combination automatically standardizes the tension, or lack of tension, upon various widths of tape; and at the same time contributes to the alignment that makes the use of a platen 13 and side guides 20 feasible. These corrugations are formed at positions which are predetermined according to the standard commercial widths of tape, or according to any other scale that may be desired, and may have a notation mark 39', as shown, conforming to and cooperating with the marks seen on the top of the platen 13, such that when the tooth 40 is in the corrugation marked 39, for example, signifying a tape three inches wide, the upright standard 12 integrally connected therewith will be in such position that one face of the disk 35 carried thereon will be one and one-half inches from the center of the apparatus. When the other standard 12 is similarly positioned a supply roll three inches long will be positioned centrally of the apparatus. This scale therefore cooperates with the scale 35 at the top of the platen, which by similar means positions centrally and in a direction parallel to the line of draft that part of the tape which is passing over the platen, with the important result that a long, straight and rather closely confined way for the tape is provided, which can be varied from one width to another rapidly, with accurate alignment with the supply roll of tape, and in a direction accurately perpendicular to the axis of the supply roll.

When the considerable diameter which the supply roll may sometimes have, with consequent long lines of draft of tape therefrom, and the very annoying distortion of the tape which results at its delivery end when the guides and draft of the tape are not all in perfect alignment, the importance of this provision will be understood, especially in any apparatus where tension is obtained by friction applied to the supply roll. In the present apparatus such friction may be desired if the stationary blade 24' shown in Fig. 7 be employed instead of that shown in Fig. 1. In that case it is only necessary to bend each of the upright standards 12 a little inward from the perpendicular (Fig. 5) so that the two have to be spread a little by the insertion of a tape roll. Then the disks 35 will exert friction upon the sides 45 of the roll. The obtaining of tension by such axial compression of the supply roll does not give results equal to those obtained by the use of the tilting blade 24, because the rolls, as a matter of practical experience, are found to be not precisely uniform in width. For this reason, when the tension is secured by a screw-adjustment as heretofore customary, applying rigid axial compression, considerable irregularities develop. The spring pressure applied in the axial direction by the present invention is capable of yielding to accommodate itself to any such irregularities of thickness, without making any appreciable difference in the tension, where a rigid compression of the roller endwise would make trouble. It is also to be noted that the disks 35 cover only a central portion of the roll, and do not extend to its periphery and so are less likely to encounter irregularities of thickness. The production of the desired tension by application of friction to the supply roll, therefore, is, in the present apparatus, entirely automatic, provided the standards 12 have been first uniformly bent inward a little toward each other, so that they will press together with a predetermined force when straightened by the insertion of the supply roll. The apparatus may then be set with the positioning teeth 40 of the standards put in the particular corrugations 39 which pertain to any particular width of tape, and a roll of tape of that width, when inserted, will be found subject to the same tension which a roll of any other width receives when the standards are put in the corrugations proper for it. The completely automatic character of this part of the apparatus is further emphasized by observing that the clamping nuts 36 may be omitted entirely, as above described.

The flexibility and spring effect of the upright standards 12 is gained in part by the introduction of a series of the slots 32, each of which cuts more than half way across the material. This renders available, for spring purposes, standards whose thickness, needed for stability, might otherwise be too great to permit of the standards affording a feasible range of spring tension.

The stability of the apparatus as a whole, produced by the general arrangement described, is another feature. The arrangement of the base as described offers facility for the introduction of considerable weight of metal there, if desired, so that the center of gravity of the apparatus is low. The position from which the tape is discharged is so low that the operator's pull upon it produces little tendency to overturn the apparatus; while the weight and rubber feet prevent it being dragged along the bench or counter on which it may be standing, so that, unlike some current types of construction, it is unnecessary to provide an abutment or bolts to hold the apparatus when it

is used. Screw holes 10" are provided by which it can be fastened rigidly down, if desired, upon a wooden counter; but the feature just mentioned permits its use on a glass counter or show case where no screw fastening is feasible; and the security is further enhanced by the fact that the draft or the tape upon the supply roll (in cases when any tension is obtained by resistance 10 of the supply roll) is directed downward toward the base, by the guide roll 27, with the result that no matter how hard the draft of tape on a frictionally held supply roll, that draft does not tend to tip the apparatus over, but merely tends to draw the supply roll and its supporting studs 34 more firmly into their seats 33.

I claim as my invention:

1. A strip serving device including in combination a device for rendering tape adhesive and a holder for a supply roll of tape comprising a standard, at each end of the axis of the supply roll, movable in the direction of the axis to various positions 25 for holding rolls of different width of tape, and stub axles supported by said standards and adapted to penetrate the adjacent ends of the roll only a short distance, thereby being capable of holding rolls of either wide 30 or narrow tape, and a base and a device thereon for engaging the standards at a plurality of locations, in symmetrical pairs, at equal distances each side of the position of closest approach.
2. A strip serving device including in combination a device for rendering tape adhesive and a holder for a supply roll of tape comprising a standard adjacent to each end of the axis of the supply roll, stub axles 40 adapted to penetrate the adjacent ends of the roll; and plates on said axles, perpendicular thereto, intervening between the roll and the adjacent standards, adapted to inclose between them the central part of the roll, the whole being arranged and adapted 45 for the said axles to let the roll slip around them and for the plates to be spring-pressed together.
3. A strip serving device including in combination a device for rendering tape adhesive and a holder for a supply roll of tape, comprising a standard at each end of the axis of the roll; a plate adapted to fit between the standard and the roll at each 55 end of the roll; and pins projecting from said plates extending inwardly to form stub axles penetrating the roll, and extending outwardly to be supported in the adjacent standard, said inwardly and outwardly extending parts being removable and replaceable with the plate to which they are attached as a single unit.
4. A strip serving device including in combination a device for rendering tape adhesive and a holder for a supply roll of 65

tape, comprising a standard at each end of the axis of the roll; a plate adapted to fit between the standard and the roll at each end of the roll; and pins projecting from said plates extending inwardly to form stub axles penetrating the roll, and extending outwardly to be supported in the adjacent standard, the outward projection having a screw and nut clamp, whereby the plate and stub axle may be held on the standard, by 70 compression of the standard between the plate and said nut, outside of the standard.

5. A strip serving device including in combination a device for rendering tape adhesive and a holder for a supply roll of 80 tape, comprising a standard at each end of the axis of the roll; a plate adapted to fit between the standard and the roll at each end of the roll; and pins projecting from said plates extending inwardly to form stub axles penetrating the roll, and extending outwardly to be supported in the adjacent standard, the outward projection having a screw clamp for engaging the standard; and there being a lug on each plate, adapted to 85 engage the standard to prevent rotation thereof with respect to the standard.

6. A strip serving device including in combination a device for rendering tape adhesive and a holder for a supply roll of 90 tape, comprising a standard at each end of the axis of the roll; a plate adapted to fit between the standard and the roll at each end of the roll; and pins projecting fixedly from said plates extending inwardly to form 95 stub axles loosely penetrating the roll, and extending outwardly to be supported in the adjacent standard; the outward projection having a screw clamp, the said standard having a slot in which the outward projection is seated, and the plate having another pin, constituting a lug projecting into said slot, thereby preventing rotation of the clamp.

7. A strip serving device including in combination a device for rendering tape adhesive and a holder for a supply roll of tape, comprising L-shaped standards adapted to support the roll; a sill for supporting the standards, provided with notches; a tooth 110 fast on each standard adapted to engage in any of said notches; and means for clamping the standard fast with its tooth so engaged.

8. A strip serving device including in combination a device for rendering tape adhesive and a holder for a supply roll of tape, comprising a sill; L-shaped standards movable thereon; means on their upright portions for holding the roll; and a terminal tooth 120 fast on each standard and projecting downward from the horizontal portion of each; there being notches in said sill in which said terminal teeth may engage; and means for holding such engagement. 125

means for fastening them on the platen at adjustable positions parallel to the direction of draft of the tape.

18. A strip serving device including in combination a device for rendering tape adhesive, a holder for a supply roll of tape, a platen between these two over which the tape passes, and tape guides adapted to lie on the platen along the edge of the tape and covering its adjacent top; said guides having end portions overlying the tape considerably and having recessed central portions overlying it only slightly, whereby the tape is held with nearly its entire width exposed 15 to receive writing.

19. A strip serving device including in combination a device for rendering tape adhesive; a holder for a supply roll of tape; a platen over which the tape passes between these two; tape guides supported on the platen; the platen having slots extending transversely inward from each side at two places, nearly to its center, forming guide slots for adjustment of said tape guides; 25 and a base for the apparatus having supports at each side for the platen forward and back of each of its said transverse slots.

20. A strip serving device including in combination a device for rendering tape adhesive; a holder for a supply roll of tape, comprising a standard at the rear; and a guide roll intervening between these two; said guide having a projecting axle 30, and the apparatus having a base 31, with slot 30 in which the axle is adapted to enter, and the part of the slot wherein the axle normally stays being slightly wider than the axle, the slot having a portion slightly nar-

rower than the axle, whereby the metal of the base forms a spring closure holding the axle in place.

21. A strip serving device including in combination a device for rendering tape adhesive, comprising a cylinder over which the tape passes; a holder including axles for a supply roll of tape; a guide roll intervening between these two; all of these having parallel axes; a base supporting them, having corrugations extending longitudinally of the line of draft of tape, whereby the holder 45 for the supply roll is standardized as to angle, in any of various positions; longitudinal guides for the tape, and means whereby said longitudinal guides may be standardized as to angle and position for guiding 50 the edges of different widths of tape on a line perpendicular to said axes.

22. A strip serving device including in combination a device for rendering tape adhesive; a holder for a supply roll of tape at an elevation; an uncovered writing bed platen over which the tape passes at a lower elevation, intervening between the two said elements; and a guide element extending below the surface of the platen, extending 55 across the path of the tape at the beginning of the platen, whereby the tape is smoothed upon the platen.

Signed by me at Rockingham, in the county of Windham and State of Vermont 70 this 17th day of June, 1914.
